UNITED STATES PATENT OFFICE.

CONSTANTINE J. KUCHTIK, OF CHICAGO, ILLINOIS.

DESIGN FOR A WATCHCASE.

60,866.

Specification for Design.

Patented Apr. 18, 1922.

Application filed November 12, 1920. Serial No. 423,740. Term of patent 7 years.

To all whom it may concern:

Be it known that I, CONSTANTINE J. KUCHTIK, a citizen of Russia, residing at Chicago, in the county of Cook and State of Illinois, have invented a new, original, and ornamental Design for a Watchcase, of which the following is a specification, reference being had to the accompanying drawing, forming part thereof, in which—

Figure 1 is a side view of the device,

Figure 2 is a front view thereof, and

Figure 3 is a rear view thereof.

The mechanism of the watch is enclosed by a non-transparent circular rim which is

disposed around its peripheral edge; and the front and rear faces of the watch are enclosed by semi-spherical transparent covers, the covers having non-transparent rims which are adapted to be carried by the first named rim. It will therefore be apparent that the watch is provided with a spherical casing which has transparent portions through which the front and rear faces may be viewed.

I claim:

The ornamental design for a watchcase, as shown.

CONSTANTINE J. KUCHTIK.
